UNITED STATES PATENT OFFICE.

CHARLES G. PERKINS, OF CAMDEN, NEW JERSEY.

ELECTRIC-ARC LAMP.

SPECIFICATION forming part of Letters Patent No. 274,370, dated March 29, 1883.

Application filed May 10, 1882. (No model.)

To all whom it may concern:

Be it known that I, CHARLES G. PERKINS, of the city of Camden, in the county of Camden and State of New Jersey, have invented 5 a new and useful Improvement in Electric Lamps, of which the following is a specification, reference being had to the accompanying drawings, forming a part of the same.

Figure 1 is a vertical elevation, partly in section, representing the working construction and general arrangement of my invention. Fig. 2 is a plan view of Fig. 1. Figs. 3 are front and side views, showing the construction of the arms *e*, *e'*, and *c*, as shown in Fig. 1. 15 Figs. 4 are illustrations in detail giving different views of the parts of which the friction-band *i'* *i²* consists. Fig. 5 is a view in detail of the rack and pinion seen in Fig. 1; and Fig. 6 is a modified form of Fig. 4, in which the friction-band and roller *g* are dispensed with, the right-angular projection upon arm *e* resting upon the disk-pin, as shown, acting as a substitute therefor. Fig. 7 represents a modified construction of the friction-band shown in 25 Fig. 4, in which the arm *e* is dispensed with, the extension *c*, which may be attached to the armature *b*, loosening or tightening its hold upon the inclosed disk according to the varying strength of magnetism in *a'* *a²*.

30 This improvement relates to that form of electric lamp in which the voltaic arc is employed by the passage of a current of electricity between two electrodes; and it consists in a novel construction of a lever-brake and encircling friction-band embracing the periphery of a rotatory disk, the lever being attached to the sliding core of an axial electro magnet or magnets, the whole being for the purpose of regulating the distance between the carbon 35 points, so that the slightest variation of resistance in the arc will result in an instantaneous response of certain mechanism, which will produce a sufficient movement of the positive electrode as consumption takes place to 40 maintain a suitable distance between the points for obtaining a light of the required intensity.

In combination with the above, my improvement further consists of a shunt-resistance 45 arrangement whose object is to establish the continuity of the circuit in the event of an ac-

cident occurring to either of the electrodes by breakage or otherwise, some such arrangement being necessary when there are a number of lamps to be operated in series. It is 55 necessary, also, that this shunt should have a resistance about equal to the normal resistance of the arc.

When it is required to put the lamp in circuit, the conductors from an electrical source 60 are connected to the binding-screws *h*, when a current of electricity will pass round the helices of magnet *a'*, which is wound with coarse wire and forms a continuous part of the conductor leading to the positive electrode. The 65 sliding core *b* is thereby drawn down into its socket in magnet *a'*, and with it the lever *c*, which is attached to this sliding core at *d* in such a manner as to allow the lever *c* sufficient play from its center as the sliding core is alternately attracted by the electro-magnets to 70 meet the requirements of the case. As a result of the attractive force of magnet *a'* upon sliding core *b*, the arm *e* of lever *c*, with its roller *g*, presses upon the hinged part of encircling 75 friction-band *i*. This friction-band, as will be seen from the drawings, is composed of two parts, *i'* *i²*, being hinged together at *i³*, and, as will be further observed, the divided part is slightly turned up at *i²*, so that the slight- 80 est movement of lever *c* will instantaneously exercise a sufficient pressure upon the periphery of the pinion-disk *j²* to prevent the sliding rack *j'* descending too rapidly or too far; also for the purpose of allowing the roller *g* to 85 move only a very little distance before the required degree of pressure is brought to bear upon hinged part *i'* at *i²*.

Inclosed within or encircled by the friction-band *i'* *i²* is a pinion-disk, *j²*, the encircling 90 friction-band embracing the periphery of the same. The pinion *j²* works in conjunction with a rack, *j'*, for the understood purpose of parting the carbon electrodes. As the carbons are consumed the resistance of the arc 95 increases, whereby magnet *a'* loses some of its power. The core *b* will then ascend a certain distance, being attracted by magnet *a²*, which now becomes stronger than *a'*. (*a²* is wound with fine wire and is placed in a derived circuit.) The altered position of lever *c* relieves 100 the pressure it exercises upon pinion-disk *j²*

by the embracing-band $i' i^2$ when the positive electrode, with the sliding rack, descends a prescribed distance, when the normal resistance of the arc is re-established and the required intensity of light secured. The small weight l is fixed to the band $i' i^2$, its object being to hold the friction-band gently pressed against and in readiness for the performance of the function assigned to lever c , with its arm e , having the roller g .

In the mechanism base-plate of the lamp, directly under the brake-wheel, is fixed a pin, 2, in such a position that a corresponding pin, 1, on the friction-band i^2 will meet the same when the lamp is in operation, thereby preventing the friction-band revolving too far, as it necessarily would in the absence of such an arrangement.

As before stated, the shunt-resistance is brought into operation when either of the electrodes are thrown out of circuit. Its action is as follows: When an electrode is put out of circuit, magnet a' , which is a continuous part of the conductor leading to the positive electrode, loses its power altogether. The sliding core b then leaves its socket in magnet a' and ascends to the limit of its distance into that of magnet a^2 , (it will be remembered that the latter magnet, being in a derived circuit, is not affected by either of the electrodes being put out of circuit,) for the reasons already stated. The contact-weight m , in consequence of the ascent of sliding core b to the limit of its distance, then falls upon the spring n , and at the same time makes connection with one end of the shunt-resistance o at o' . On referring to the drawings it will be seen that spring n is connected with the positive pole of the lamp. Now, if a current of electricity passes along this spring, which is touched by contact-weight m , it passes in at the positive end of the shunt-resistance, and the other end being connected with the negative pole of the lamp, the circuit is complete, and the other lamps in the same series remain unaffected. The contact-weight

must of course be insulated from the metallic lever-extension e' , to which it is secured. When the electrodes are again brought together, magnet a' is once more energized and the arc re-established, because the shunt o is of higher resistance than the electrodes when the two points touch, and the current will find the passage of least resistance. The shunt-resistance is therefore thrown out of circuit in consequence of the energized condition of magnet a' and the resulting altered position of lever c , as already described.

Having thus described my invention, what I claim as new, and desire to secure by Letters Patent, is—

1. In electric-arc lamps, the mechanism for regulating the distance to be maintained between the electrodes, which consists in the combination of the electro-magnets $a' a^2$, having the sliding core b , to which is attached the lever c , having the arm e , with roller g and arm e' , the divided friction-band $i' i^2$, embracing the revolving disk j^2 , and the weight l , in conjunction with a rack and pinion connected with the positive electrode of the lamp, substantially as described.

2. In electric-arc lamps, the combination of the divided friction-band $i' i^2$, hinged at i^3 and turned up at g^2 , the rotatory disk j^2 , with the roller g , rack g' , and pinion j^3 , substantially as described, and for the purpose set forth.

3. In electric-arc lamps, the combination of the encircling friction-band $i' i^2$, embracing the periphery of the disk j^3 , and friction-band weight l , with the lever c , arm e , roller g , arm e' , shunt-resistance o , and spring n , substantially as described.

4. In electric-arc lamps, the combination of the encircling friction-band $i' i^2$ with the arm e and roller g , arm e' and weight l , and pins 1 and 2, substantially as described.

CHARLES G. PERKINS.
